(No Model.)

W. R. McGUIRE.
RAILWAY GATE.

No. 487,538.

Patented Dec. 6, 1892.

UNITED STATES PATENT OFFICE.

WILLIAM RUSSELL MCGUIRE, OF FORT DODGE, IOWA.

RAILWAY-GATE.

SPECIFICATION forming part of Letters Patent No. 487,538, dated December 6, 1892.

Application filed June 13, 1892. Serial No. 436,543. (No model.)

To all whom it may concern:

Be it known that I, WILLIAM RUSSELL MCGUIRE, of Fort Dodge, in the county of Webster and State of Iowa, have invented certain new and useful Improvements in Railway-Gates; and I do hereby declare the following to be a full, clear, and exact description of the invention, such as will enable others skilled in the art to which it appertains to make and use the same.

This invention contemplates certain new and highly-useful improvements in railway-gates or cattle-guards; and it has for its object the production of cheap, simple, and highly-efficient mechanism whereby a gate or guard can be readily and easily operated or thrown open by a train moving in either direction, said gate or guard being automatically closed after the train has passed.

The invention comprises the detail construction, combination, and arrangement of parts, substantially as hereinafter fully set forth, and particularly pointed out in the claims.

In the accompanying drawings, Figure 1 is a plan view of my improved railway-gate. Fig. 2 is a transverse sectional view thereof on the line *x x*, Fig. 1. Fig. 3 is a sectional view on the line *y y*, Fig. 1.

Referring to the drawings, *A A'* designate the rails, and *a a'* two corresponding operating-bars pivotally hung along the inner sides of said rails by means of crank-rods *a²*, extended through holes in the vertical webs of the rails. These operating-bars normally occupy a position on a line with or slightly above the tread of the rails. To the inner end of each bar is secured a short bar *a³*, which forms an extension thereof and is provided with inner rack-teeth *a''* for engaging a pinion *a⁴*, whose shaft or stud is supported by a bracket *a⁵*, made fast to a tie or sleeper *T*. The rack-bar of the operating-bar *a* extends over this pinion, while the rack-bar of the operating-bar *a'* is extended beneath said pinion, the teeth of both rack-bars always being in engagement with said pinion. Hence the movement of one operating-bar will effect the movement of the other bar in the opposite direction.

B B' designate two sliding bars loosely held to the outside of each rail by nutted bolts *b*,

projecting from the rail-webs through slots *b'* in said bars. To the outer ends of these bars are connected rods *b²*, which at their outer ends are loosely connected to extended ends *b³* of two of the crank-rods *a²*.

C designates the gate or guard, which is formed in two independent sections *d d'*, each section being supported near its center and outer end by inner and outer rods *d² d³*, which are pivotally attached at their lower ends to tie *T*, so as to effect the backward and forward movement of each section. A spring *d⁴*, attached to each end of this tie and bearing against the end of the adjacent section, serves to hold the latter closed. To the outer rod *d³* of each gate-section are pivotally connected the inner ends of two divergent rods *d⁵ d⁶*, which at their outer ends are attached to the sliding bars *B B'* near the outer ends of the latter. From what has been said it will be seen that a train moving in either direction will upon striking against the pivoted operating-bars effect the lowering and forward movement thereof, the same turning the pivoted crank-rods, and by reason of the rack-bar extensions the movement of the operating-bars on one side of the gate will effect the movement of those on the other side thereof. This movement of the pivoted operating-bars will cause the outer sliding bars *B B'* to move forward toward each other and through the agency of the divergent rods *d⁵ d⁶* cause the gate-sections to be thrown backward, withdrawing their inner ends from across the track, so as to permit the train to pass without striking thereagainst. As soon as the last wheels of the rear car of the train pass beyond the pivoted rods the gate-sections will be returned to their normal positions by the springs bearing against them.

The advantages of my invention are apparent to those skilled in the art to which it appertains, and it will be specially observed that a railway-gate or cattle-guard thus constructed is simple, inexpensive, and durable.

I claim as my invention—

1. The herein-described improved railway-gate or cattle-guard, comprising the gate formed in two sections capable of moving backward and forward, pivoted operating-bars extended along the sides of the rails on each side

of said gate and having their inner ends in fixed relation with each other, the pivoted crank-rods supporting said bars, the outer sliding bars connected to and operated by said 5 crank-rods, and the divergent rods connected to said sliding bars and also to said gate-sections, substantially as set forth.

2. The herein-described improved railway-gate or cattle - guard, comprising the gate 10 formed in two sections, pivoted operating-bars extending along the sides of the rails on each side of said gate and having overlapping rack-bars at their inner ends, the pinions between said rack-bars, the outer sliding bars operated by said former bars, and the divergent 15 rods connected to said sliding bars and also to said gate-sections, substantially as set forth.

3. The herein-described improved railway-gate or cattle - guard, comprising the gate 20 formed in two sections and having inner and outer pivoted supporting-rods, the operating-bars extended along the inner sides of the rails, the pivoted crank-rods supporting said bars, the rack-bar and pinion connections between the inner ends of said operating-bars, 25 the outer sliding bars, the rods connected to the ends thereof and also to extended ends of said crank-rods, and the divergent rods piv-

otally connected to said outer sliding bars and also to the outer supporting-rods of said gate-sections, substantially as set forth.

4. The herein-described improved railway-gate or cattle - guard, comprising the gate formed in two sections having inner and outer pivoted supporting-rods, the springs bearing 35 against the outer ends of said gate-sections, the crank-rods supported by the rails, the operating - bars pivotally supported by said crank-rods and having overlapping rack-bars at their inner ends, the pinions located between said rack-bars, the outer sliding bars having slots, the nutted bolts projecting from the rails through said slots, the rods connected to the ends of said outer sliding bars and also to the extended ends of said crank-rods, 40 and the divergent rods pivotally connected to said sliding bars and also to said gate-sections, 45 substantially as set forth.

In testimony whereof I have signed this specification in the presence of two subscribing witnesses.

WILLIAM RUSSELL McGUIRE.
